(57) **CLAIM**

The ornamental design for a display screen or portion thereof with animated graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a first embodiment of a front view of a display screen or portion thereof with animated graphical user interface showing a first image in a sequence;

FIG. 2 is a second image thereof; and

FIG. 3 is a third image thereof.

FIG. 4 is a second embodiment of a front view of a display screen or portion thereof with animated graphical user interface showing a first image in a sequence;

FIG. 5 is a second image thereof; and,

FIG. 6 is a third image thereof.

The outermost broken lines in the figures show a display screen or portion thereof, and form no part of the claimed design. The other broken lines in the figures show portions of the graphical user interface that form no part of the claimed design.

In the first embodiment, the appearance of the animated image sequentially transitions between the images shown in FIGS. 1-3. In the second embodiment, the appearance of the animated image sequentially transitions between the images shown in FIGS. 4-6. The process or period in which one image transitions to another forms no part of the claimed design.

FIGS. 1-3 show eleven circles in a horizontal arrangement. The solid black surface shading within one of the eleven circles in FIGS. 1-3 represents a color contrast.
